UNITED STATES PATENT OFFICE.

THOMAS W. SMALL, OF CLEVELAND, OHIO, ASSIGNOR TO THE ACME INDICATOR COMPANY, OF CLEVELAND, OHIO, A CORPORATION OF OHIO.

STREET-INDICATING APPARATUS.

1,179,770.

Specification of Letters Patent. Patented Apr. 18, 1916.

Application filed January 9, 1913. Serial No. 741,131.

To all whom it may concern:

Be it known that I, THOMAS W. SMALL, a citizen of the United States, residing at Cleveland, in the county of Cuyahoga and State of Ohio, have invented a certain new and useful Improvement in Street-Indicating Apparatus, of which the following is a full, clear, and exact description, reference being had to the accompanying drawings.

10 This invention relates to street indicating machines, of the general type shown in my prior applications Nos. 529,681, filed November 24, 1909 and 572,349, filed July 16, 1910, and particularly to improvements on 15 the construction of the machines shown therein, with certain resultant advantages thereover.

The applications referred to relate to machines of this character which are used on 20 railway cars for indicating streets or stations as they are approached. The machines set forth in these applications comprise, generally, a strip of flexible material which bears the indications of the stations and 25 which has each of its ends attached to a spring drum, the spring drums acting in opposite directions to keep the strip taut. The strip is shifted from one drum to the 30 other by a driving roller over which the strip passes in its course from one drum to the other. The driving roller is rotated by a spring motor, which is controlled by an electrically actuated escapement mechanism, the 35 escapement mechanism being operated when certain contacts are made, as between a member carried by the trolley pole of the car and stationary contact brushes which are placed in advance of the stops or stations along the track.

40 Such construction as that just described requires the winding of the motor spring at frequent intervals and the reversal of the mechanism at the end of each trip. Since the movement of the strip is controlled, indirectly, by the escapement mechanism, it 45 will be seen that if the strip should, through any cause, be thrown out of correct position and thus give inaccurate indications, it would require the time and services of some 50 one to readjust it.

The objects of my present invention are; to provide a machine of this character which will operate positively and quietly; wherein the extent of the intermittent movements of 55 the strip is controlled by means carried by

the strip, which thus renders accurate the indications of the stops or stations as they are approached; which is operated by electrical means and reversed automatically at the end of each trip; and one which includes 60 certain electrical contrivances for promoting positive and accurate operation of the machine under all conditions.

Furthermore, I provide by my present invention, a machine of great capacity, 65 constructed in a compact manner; one which is especially adapted for use on cars which traverse routes which are divided, for a certain portion of their extent, one branch being passed over when traveling one direction 70 and the other branch being included on the return trip.

These, and further objects which will become apparent during the course of this description, I attain in a machine consisting 75 of the combinations of elements set out in the claims annexed hereto, and illustrated in the accompanying drawings forming a part hereof, wherein:

Figure 1 is a perspective of my street indicating machine; Fig. 2 a central, vertical transverse section thereof; Fig. 3 a plan view of the machine, the casing appearing in section; Fig. 4 an end elevation of the machine, the casing being removed in this 80 and the subsequent figures; Fig. 5 a front elevation; Fig. 6 a vertical section through the operating mechanism, taken on the line 6-6 of Fig. 5 and looking in the direction of the arrows; Fig. 7 a section on line 7-7 85 of Fig. 6; Fig. 8 a detail, showing the operative position of certain parts appearing in Fig. 8; Fig. 9 is a detail of the contact rollers which coöperate with contact bars upon the indicating strip (a portion of which is shown in said figure) for limiting the movement of the strip; Fig. 10 is a diagrammatic view showing the relative positions of the two contact rollers as associated with the contact bars along the strip; Fig. 11 is a detail of the governor which controls the speed 90 of operation of the machine; Fig. 12 a sectional view on the line 12-12 of Fig. 11; and Fig. 13 a diagram of the electric circuits involved in the carrying out of my invention.

It will be noted, upon a comparison of the machine which forms the subject matter of this application and the machines which are shown in my former applications, that I 110

have, in my latest development, widened the indicating strip, and the additional space thereby provided may be used for advertising purposes or for bearing instructions to the passengers in the car.

In the drawings, 1 represents a rectangular casing of a sufficient size to accommodate the frame and operating parts of my machine, and is provided with a rear wall 2. 10 The front of the casing is adapted to be closed by a face plate 3 which is secured, at its upper edge, to the casing 1 by means of hinges 4. Straps 5, which are secured to the bottom of the casing and overhang its forward edge, are adapted to project through slots near the lower edge of the face plate 3, one of said straps extending beyond the front surface of the face plate 3 a sufficient distance to receive the bail of a padlock 6 with 15 in a hole in its forward end. The face plate 3 is provided at about its longitudinal center, with an opening 7, through which the street or station indications upon the strip may be read. Openings 8, located on either 20 side of the opening 7, reveal the matter which occupies that portion of the strip between its edges and the column of street or station indications.

The frame of the machine comprises right 30 and left hand end plates 10 and 11, respectively, which are spaced apart and rigidly held in proper relation to each other by the tie rods 12, 13, 14 and 15. Journaled within the end plates 10 and 11 are the trunnions 16 and 17 of the drums 18 and 19, respectively. To the left hand end of the drum 18 is secured a spur gear 20, and a similar gear 21 is secured to the opposite end of the drum 19. A shaft 22, which is also journaled in 35 the plates 10 and 11, has loosely mounted on its left hand end a spur gear 23 which is adapted to mesh with the gear 20 on the drum 18. Meshing with the gear 21 of the drum 19 is a gear 24, similar to the gear 23 and mounted loosely upon the shaft 22 near 40 its right hand end. One end of a spiral spring 25 is secured to the gear 24 and the other end to the gear 23. The parts are so arranged that, when assembled, the spring 45 25 will always be under a tension, the tension varying in different machines in proportion to the length of the strip.

A driving roller 27, which is shown in the drawings as consisting of a shell with 50 solid ends 28, is provided at its right hand end with a stub shaft 30 which is journaled in the end plate 10 near its lower forward corner and projects therethrough a sufficient distance to permit a pinion 31 to be secured thereto. A stub shaft 32, which projects from the opposite end of the feed roller, is journaled within the plate 11 and has secured to its projecting end a gear 33. The strip 35, upon which appear the street or 55 station indications, has one of its ends se-

cured to the drum 18 and after passing over the idle roller 36, which is journaled in the plates 10 and 11 near their upper forward corners, it passes over the driving roller 27, and thence over the idle roller 37 which is 60 located above and slightly forward of the center of the roller 27 and is also journaled in the end plates 10 and 11, and finally passes on to the drum 19 to which its opposite end is secured. To compensate for the 65 variations in diameter of the drums 18 and 19, as the strip is wound from one to the other and for the purpose of keeping the strip taut, I have provided a tension means consisting of the aforesaid gears 23 and 24, 70 the shaft 22 and the spring 25 which is connected to said gears and interposed between the gears 20 and 21, secured to the drums 18 and 19 respectively. By this flexible line of 75 gearing just described, there is a continual opposition existing between the two drums 18 and 19 which is sufficient to keep the strip taut, notwithstanding the fact that one 80 drum is being driven by the other without the intervention of the strip.

As will be seen by referring to Figs. 2 and 9, the tie rod 13 has yieldingly secured to it, by means of springs 40, a pair of arms 41 and 42 which are composed, preferably, 85 of fiber or some other insulating material. Contact rollers 43 and 44 are carried by extensions which are made of some conducting material, such as brass, and which are secured to the arms 41 and 42 by means of binding posts 45 and 46. Adapted to co-operate with the rollers 43 and 44 are contact bars or pins 47, which are secured to the indicator strip between the various street or station indications. It will be noticed 90 from Figs. 9 and 10 that the points of contact between the rollers and the strip 35 are out of transverse alignment, permitting but a short duration of the contact between both of the rollers 43 and 44 and the contact bars or pins 47.

Three contact arms 48, 49, and 50, somewhat similar to those just described, but considerably longer, are mounted loosely upon the tie rod 15 and carry contact rollers 51, 52, and 53, respectively, at their forward 105 ends. Each end of the indicating strip is provided with a contact plate 82 which is adapted to ride under the middle roller 52 and one of the rollers 51 or 53, when the car upon which the machine is used has 110 reached the end of its trip. It is the electrical contacts thus provided which secure accurate registration of the indications with the opening 7 and accomplish the automatic reversal of the mechanism of the machine 115 previously referred to, and the means associated with the parts just mentioned for accomplishing the reversal will be hereinafter fully described.

Secured to the end plate 10 are the sole- 120

noids 54 and 55. The solenoid 54 is provided with a divided core, the parts of which are designated 56^a and 56^b. The portion 56^a has secured to its forward end a block 57 of non-magnetic material. The block projects downwardly and has secured to its rear face, near its lower end and in vertical alinement with the core of the solenoid, a rod 58 which projects rearwardly 10 from the block 57 and is guided in a bracket 59. A spiral spring 60, which is interposed between the bracket 59 and the block 57, tends to maintain the core portion 56^a in its outward position. The solenoid 55 is identical with the solenoid 54 and has a divided core consisting of the parts 61^a and 61^b, the part 61^a having secured to its forward end the block 62 which carries a rod 63, projecting at its rear end through the bracket 20 59 and fitted with a spiral spring 64.

Secured to the end plate forward of the solenoids 54 and 55 are blocks 65 and 66 to the outer ends of which there is secured, by screws 67, a plate 68. The front edges of 25 the blocks carry a plate 69. Journalized in the end plate 10 and in the plate 68 and located midway between the longitudinal centers of the solenoids, is a shaft 70 which has secured to it, near its inner end and 30 adjacent the end plate 10, a spur gear 71 which is adapted to mesh with the pinion 31 on the stub shaft 30 of the feed roller 27 heretofore referred to. Fixed to the shaft 70, substantially at its center, are two 35 ratchet wheels 72 and 73, the teeth of one ratchet wheel being inclined in opposite direction to those on the other. Arms 74 and 75 have their inner ends loosely journaled upon the shaft 70 alongside the ratchet 40 wheels 72 and 73 and to their outer ends are pivoted pawls 76 and 77, said pawls being adapted to engage the teeth of their respective ratchet wheels. Links 78 and 79 connect the outer ends of the pawls 76 and 45 77 to the blocks 57 and 62 respectively, which are secured to the outer ends of the forward core sections of the solenoids.

By this construction, it will be seen that, when the solenoid 54 is energized, its core 50 will be drawn inwardly, moving the blocks 57 and rod 58 rearwardly against the tension of the spring 60. As the block 57 starts on its rearward movement, it will, because of the connection of the pawl 76 to the link 55 78, cause the pawl 76 to swing upon its pivot until the nose of the pawl engages a tooth of the ratchet 72, and the further movement of the parts will result in a partial rotation of the shaft 70, thus causing 60 the gear 71 to rotate the pinion 31, and consequently the feed roller 27, in a direction to cause the indicating strip to be fed downwardly over the roller 36 and from the drum 18 onto the drum 19. Screws 80, which are 65 threaded through the plate 69, form adjust-

able stops to limit the forward movement of the arms 74 and 75 which movement is influenced by the springs 81 connected thereto and the movement of the lower ends of the pawls 76 and 77, and the excess movement 70 of the blocks 57 and 62 over that of the arms 74 and 75 is sufficient to rock the pawls 76 and 77 out of engagement with their respective ratchet wheels, when the parts are in their normal positions. The rear end portions 56^b and 61^b of the cores are secured 75 to a plate 85, to which there is secured a slide bar 86 guided within a slot in the outer end of the bracket 59 and beneath a plate 87 which is carried by, and spaced from, the 80 plate 68. Secured to one side of the forward end of the slide bar 86 is a block 88 having a curved rear face which corresponds to the curvature of a disk 89 which is secured to the outer end of the shaft 70. The periphery of the disk 89 and the inner curved face of the block 88 are milled to form a locking engagement between the two members when they are together. A spring 90 which is anchored at its rear end to the 90 bracket 59 and at its forward end to a post projecting inwardly from the slide bar 86, holds the bar normally in a rearward position and maintains the engagement of the block 88 with the disk 89. It will be seen, 95 therefore, that when either of the solenoids is energized, the rear core portion thereof will be drawn forwardly and, because of its connection with the slide bar 86 through the plate 85, the said slide bar will be advanced a sufficient distance to unlock the shaft 70 by the disengagement of the block 88 and the disk 89 and permit of the operation of the machine and that, when the solenoid is deenergized, the block 88 will 100 engage the disk 89 and prevent undue movement or "overthrow" of the parts and especially of the strip.

In the path of movement of the rods 58 and 63, but slightly beyond the normal limit 110 of said movement, are contact plates 91 and 92, the purpose of which will be brought out in the description of the electrical circuits that are involved in the operation of the machine. These contact plates are 115 mounted upon a block 93 of insulating material, which in turn is secured to the base 94 of the bracket 59. The ends of the rods 58 and 63, which are adapted to engage the contact plate 91, are capped with insulating 120 material, as indicated at 95.

The speed of the operation of the machine is controlled by a governor which is shown in detail in Figs. 11 and 12 of the drawings. The governor comprises a block 96, preferably of fiber or other approved friction material, in which there is a circular opening 97. A pair of semi-circular weights 98 occupy the opening 97 and are held apart and 125 in contact with the wall of the opening by 130

light springs 99 which are contained within recesses formed in the adjacent faces of the weights. The said adjacent faces of the weights 98 are also provided, at their centers, with transverse curved grooves for the accommodation of a shaft 100. The ends of a pin 101, which passes through the shaft 100 and is secured thereto, occupy holes which pass vertically through the weights 98. The reduced ends of the shaft 100 are journaled in the left hand end plate 11 of the machine and in a plate 102 which covers the front of the block 96 and to which it is secured as by the screws which pass through the block and are threaded into the plate 11. A pinion 103, which is secured to the outer end of the shaft 100, meshes with a gear 104, journaled upon a stub shaft 105 projecting from the end plate 11 (see Fig. 5). A pinion 106 which is secured to the gear 104 meshes with the gear 33 upon the shaft 32 of the feed roller 27. Therefore, when the feed roller is rotated, the governor weights within the opening 97 in the block 96 are caused to spin and, by centrifugal action, will greatly increase the friction between the weights 98 and the curved wall of the opening 97 and retard the operation of the machine. This form of governor is noiseless and is, therefore, very satisfactory for use in connection with these machines.

It will be seen, upon referring to Figs. 1 and 2, that the opening 7 in the face plate 3 is double the height of that portion of the strip 35 which is occupied by a single street-indication and that half the opening is covered by a shifttable spring plate 110. Fig. 2 shows this plate as being curved so that its corners bear against the rear side of a retaining flange 111, which surrounds the opening 7, and shows the curved back of the plate as bearing against the glass 112 with which the opening is provided and which may be held in place by any approved and well known means, such as by corner pieces 113. When the spring plate 110 is in the position shown in the drawings, its lower corners are retained within the notches 114 (formed within the side grooves of the retaining flanges 111) through the resiliency of the plate. To shift the plate to its lower position, its lower edge is sprung toward the glass a sufficient distance to disengage its corners from the notches 114, when the plate may be easily shifted to reveal that portion of the strip 35 previously covered and conceal the indications formerly displayed through the lower half of the opening 7. By this arrangement, I provide for a condition which often arises in the routing of city street cars and which requires that the reverse trips of the car be made on different thoroughfares. This makes it necessary to include, on the strip 35, two sets of indications, one set reg-

istering with the upper half of the opening 7 and the other set with the lower half, the set not in use being covered by the plate 110.

Explaining the circuits by reference to Fig. 13, A represents the trolley wire, B a contact brush such as covered by my Patent No. 937,107 and which has electric connection to the trolley wire, there being one of such brushes in advance of each of the stops or stations along the car line. C represents the trolley wheel carried by the pole D, and E is a contact sleeve adapted to coöperate with the brush B when the pole travels past the latter. When contact is made between the brush B and the sleeve E, a current passes through the wire a , through the magnet b , the wire a' to the arm c , through which it passes to the contact d , thence through the wire a^2 to the solenoid 54, and thence through the wire a^3 to the ground. The solenoid 54 will thus be energized and operate the machine, as heretofore described, to move the indicating strip 35 in the direction indicated by the arrow. The current thus supplied to the solenoid 54 will be sufficient to operate the machine provided that the car were traveling slowly, or were actually stopped with the sleeve E in engagement with the brush B. But considering the speed at which the average street car runs, it will be obvious that the contact will be of such brief duration that nothing more than a slight impulse would be transmitted to the feed roller, especially when the speed of such feed roller is under the control of the governor previously mentioned. For that reason I provide means, operative by the circuit just described, for introducing into the circuit additional current direct from the constant supply afforded by the trolley wire and wheel, which means I will now describe.

Immediately upon the energizing of the magnet b , the lever e is swung upon its pivot through the attraction of the magnet for its armature, which is secured upon the end of said lever. The opposite end of said lever swings into contact with the overhanging end of the arm f to which current is supplied direct from the harp of the trolley wheel through the wire g . From the arm f the current passes through the lever e to the wire g' a portion of the wire a , through the magnet b , the wire a' , and so on through the path previously described, to the solenoid 54. By this means it will be seen that I may supply current to the solenoid 54 for any desired length of time after the initial supply through the brush B and sleeve E is instituted. The length of time the solenoid 54 is energized is dependent entirely upon the movement of the strip 35, and for that reason I include upon said strip the contact bars 47 which control, through

their coöperation with the contact rollers 43 and 44, the contact between the arm *f* and the lever *e*, as will become apparent from the following description:—When the bar or pin 47 passes beneath the contact rollers 43 and 44, a circuit is established through the wire *h* (which branches off from the wire *g*) through the solenoid *i* and thence through the wire *h*' to the contact roller 43, 10 through the contact bar or pin 47, the roller 44, wire *h*², and through the resistance *j* to the ground. When the solenoid *i* is energized, it pulls the arm *f*, against the action of the spring *k*, out of contact with the lever 15 *e* and thus breaks the circuit and stops the supply of current from the trolley wire. At the same time, the magnet *b* is deenergized, releasing its armature, and the lever *e* is returned to normal position by the spring 20 *l*. Since the indicating strip 35 is preferably made of a fabric which might easily be scorched or burned, it is important that no arcing take place between the contact bars or pins 47 and the rollers 43 and 44. I 25 therefore secure to the lower end of the arm *f*, and insulated therefrom, a contact segment *m* which is adapted to engage the contact spring *n* when the said arm is swung about its pivot by the solenoid *i*. The instant, therefore, that contact is made between contact bars 47 and the rollers 43 and 44, the segment *m* is moved into contact with the spring *n* and a part of the current passing through the solenoid *i* is carried to the 30 ground through the wire *o*, the segment *m*, the contact spring *n* and the wire *o*'.

The parts above described whereby the feeding circuit is maintained closed after the momentary contact between the sleeve *E* 40 and the brush *B* is broken, constitute in effect a relay whereby the feeding circuit is operative until such time as the strip moves the predetermined distance between two of the contact bars or pins, whereupon the 45 feeding circuit is opened.

To provide for an emergency arising from the absence of any of the contact bars or pins 47, caused, for instance, by the loosening or the coming off of said bars or pins, 50 or from the contact bars or pins passing beneath the rollers 43 and 44 so rapidly that the proper contact will not be made, I employ, as a safe-guard, the contact springs 91 and 92 which are actuated by the ends of the 55 rods 58 and 63, secured to the cores of the solenoid by the blocks 57 and 62. When the core of either of the solenoids has been drawn in a sufficient distance to operate the machine and move the strip the required 60 amount, the end of the rod carried by the core presses the contact spring 91 against the spring 92, causing the current which flows through the solenoid *i* to pass through wires *p* and *p*' to the ground.

65 The machine is reversed by conducting the

current through the solenoid 55 instead of the solenoid 54 and this is accomplished by the shifting of the arm *c* out of engagement with the contact spring *d* and into engagement with the contact spring *d*', the arm 70 being shifted in the following manner:—As mentioned in the foregoing description, a contact plate 82 is secured to each end of the indicating strip 35, and when either of these plates engages the roller 52 and either 75 of the rollers 51 or 53, one or the other of the solenoids *q* or *q*' is energized to effect the shifting of the arm *c*. With the parts in the position shown in the diagram and assuming that the plate 82 is bridging the 80 contact rollers 51 and 52 and that the engagement of the sleeve *E* with a brush *B* has supplied current to the machine, a circuit will be established through the wire *a*, the magnet *b*, the wire *a*', the arm *c*, and the contact spring *d*, identical with the circuit first described, but at this point only a part 85 of the current is transmitted to the solenoid, the remainder of the current flowing through the wire *s*, the solenoid *q*, and the wire *s*', to the roller 51, and passing through the plate 82 to the roller 52 it is conducted to the ground through the wire *s*² and *h*².

When the solenoid *q* is energized it exerts an initial pull upon the lever *c*, and said lever, by reason of its inertia, will swing into contact with the spring *d*', and the current from the arm *c* is then conducted through the wire *t* to the solenoid 95 55. There is no contact bar 47 to engage the rollers 43 and 44 when the plate 82 is in engagement with its respective rollers, but the machine will stop as soon as the arm *c* leaves the spring contact *d*, thereby breaking the circuit through which current is supplied to the solenoid 54.

A manually operated switch *x* has been included in the trolley circuit for the purpose of advancing the strip at will should it, through any cause, (as, for instance, the 100 disability of one or more of the brushes *B*) be thrown out of proper relation to the streets or stations. This switch performs the same function as the switch comprising 105 the lever *e* and the arm *f*.

Having thus described my invention, what I claim is:

1. In an apparatus of the character described, the combination of a strip, means for feeding the same intermittently a predetermined distance, and means acting to automatically suspend the operation of the feeding device should the strip be moved beyond such predetermined distance. 120

2. In an apparatus of the character described, the combination of a strip, means including a solenoid core for feeding said strip, means operating to automatically suspend the feeding movement when the strip has been moved a predetermined dis- 125 130

- tance, and means controlled by the movement of said core for automatically suspending such feeding movement when the predetermined distance has been exceeded.
5. 3. In an apparatus of the character described, the combination of a strip, means including a solenoid core for feeding said strip intermittently predetermined distances, and means also controlled by the 10 movement of the core for suspending the feeding of the strip should it be carried beyond such predetermined distance.
4. In an apparatus of the character described, the combination of a strip, a solenoid having a divided core, means including 15 one of the core members for feeding the strip, and means controlled by the other core member for blocking the movement of the strip.
20. 5. In an apparatus of the character described, the combination of a strip, means for moving said strip, other means for locking said strip against movement, and a solenoid having a divided core, the core portions 25 acting simultaneously to operate the feeding mechanism and to render ineffective the locking mechanism.
6. In an apparatus of the character described, the combination of a strip, an electric 30 circuit for feeding said strip predetermined distances, contacts arranged to momentarily close said circuit, a relay in said circuit, means for rendering the relay operative to maintain the feeding circuit 35 closed after the momentary contacts are separated, means including a contact on the strip for rendering the relay inoperative, and means whereby arcing at the contact on the strip is prevented when the relay is thus 40 rendered inoperative.
7. In an apparatus of the character set forth, the combination of a strip, an electric circuit for feeding the strip, contacts arranged to close said circuit momentarily, a 45 relay in said circuit and adapted to maintain the same closed after the separation of said contacts, said relay including a movable contact member which is adapted, when in normal position, to close the feeding circuit, a contact on the strip, a two-branched circuit, one branch whereof includes the strip contact and is adapted when closed to shift the movable contact member and the second branch whereof is closed by the movable contact member when so shifted to 55 short circuit the strip contact.
8. In an apparatus of the character set forth, the combination of a strip having contact members, an electric circuit for feeding said strip, contacts arranged to close 60 said circuit momentarily, a relay in said
- circuit arranged to maintain the same closed after separation of said contacts, a circuit for opening the first mentioned circuit and including the contact members on the strip, and means controlled by the second circuit 65 for short-circuiting the same when closed by the strip contact members.
9. In an apparatus of the character set forth, the combination of a strip having 70 spaced contact members thereon, a feeding circuit for said strip, a circuit including said contact members for breaking the first-mentioned circuit, and means additional to the second circuit for breaking the feeding 75 circuit.
10. In an apparatus of the character set forth, the combination, of a strip, spaced contact members thereon, an electric circuit for feeding the said strip, a circuit including the contact members for breaking the feeding circuit, and a circuit, additional to the second circuit, for automatically breaking 80 the feeding circuit should the second circuit remain open.
85. 11. In an apparatus of the character set forth, the combination of a strip, mechanism for feeding said strip, a circuit for operating said mechanism, a second circuit controlled by the strip for breaking the first mentioned circuit, and a circuit controlled by the said feeding mechanism for breaking the first mentioned circuit should the second circuit be inoperative for such purpose.
90. 12. In an apparatus of the character set forth, the combination of a strip, mechanism for feeding said strip, a solenoid having a core for operating said mechanism, a circuit controlled by the strip for breaking the solenoid circuit, and a circuit controlled by the solenoid core also for breaking the solenoid circuit should the second circuit be inoperative for such purpose.
95. 13. In an apparatus of the character set forth, the combination of a strip, means for feeding the same, contact bars or pins carried thereby, and a circuit coöperating with said bars or pins, and including a pair of rollers, said rollers being arranged to simultaneously engage each pin or bar, such simultaneous engagement occurring when a pin or bar has passed the perpendicular center of one roller and before the pin or bar reaches the perpendicular center of the other roller.
100. 115. In testimony whereof, I hereunto affix my signature in the presence of two witnesses.

THOMAS W. SMALL.
